(57) **CLAIM**

We claim the ornamental design for the lighting apparatus, as shown and described.

DESCRIPTION

FIG. 1 is a bottom perspective view of a lighting apparatus of the present invention;

FIG. 2 is a top perspective view of a lighting apparatus of FIG. 1;

FIG. 3 shows a bottom view of the lighting apparatus of FIGS. 1 and 2;

FIG. 4 shows a top view of the lighting apparatus of FIGS. 1 and 2;

FIG. 5 shows a left side view of the lighting apparatus of FIGS. 1 and 2;

FIG. 6 shows a right side view of the lighting apparatus of FIGS. 1 and 2;

FIG. 7 shows a front view of the lighting apparatus of FIGS. 1 and 2; and,

FIG. 8 shows a rear view of the lighting apparatus of FIGS. 1 and 2.
